UNITED STATES PATENT OFFICE.

EDWIN L. BRUNDAGE, OF EAST ORANGE, NEW JERSEY.

HORSE-COLLAR.

SPECIFICATION forming part of Letters Patent No. 699,143, dated May 6, 1902.

Application filed October 27, 1898. Serial No. 694,651. (No model.)

To all whom it may concern:

Be it known that I, EDWIN L. BRUNDAGE, a citizen of the United States, residing at East Orange, in the county of Essex and State of New Jersey, have invented certain new and useful Improvements in Horse-Collars; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

15 This invention relates to certain improvements in that class of horse-collars represented by the one shown in my prior patent, No. 599,981, granted March 1, 1898, the objects of the present improvements being to prevent 20 injury to and secure greater comfort for the horse in the event of a puncture and collapse of the inflated pneumatic sack within the collar, to reduce the cost of construction, to render the collar more comfortable to the animal 25 at the hinge end thereof, and at the same time provide a hinge that will be more simple, durable, and firm in its connection with the frame, and to secure other advantages and results, some of which may be referred to hereinafter in connection with the description of 30 the working parts.

The invention consists in the improved pneumatic horse-collar and in the arrangements and combinations of parts of the same, 35 all substantially as will be hereinafter set forth, and finally embraced in the clauses of the claim.

Referring to the accompanying drawings, in which like letters of reference indicate corresponding parts in each of the several figures, Figure 1 is a front elevation of the improved collar complete. Fig. 2 is a detail view showing certain parts removed to show the frame more clearly. Fig. 3 is a section, on an enlarged scale, taken at line *x*, Fig. 1. Fig. 4 is a section taken on line *y*. Fig. 5 is a front detail view of a certain hinge attached to the frame of the collar. Fig. 6 is a plan of the same. Fig. 7 is a detail view of an improved pneumatic sack adapted to be inserted within the leather covering of the collar. Fig. 8 is a section of the same on line *z*. Fig. 9 is a

detail section of the upper part of the collar; and Fig. 10 is a section at line *x'*, Fig. 9. Figs. 11 and 12 are sectional details showing a catch 55 at the lower part of the frame, and Fig. 13 illustrates a method of covering the frame to adapt it to receive the pneumatic sack.

In said drawings, *a* indicates the hames of the collar, hinged together at their upper ends, 60 as at *c*, and provided with the draft-eyes *a'*, which may be integral therewith. *b b* are tubular frame-sections, also hinged together at their upper ends upon the same hinge-pin *c* as the hames, the said frame and hame sections being curved to properly conform to the shape of the horse's neck and to hold the flexible parts of the collar firmly and securely in place. The frame *b* is preferably partially covered preliminary to its insertion in the collar with a partial covering *e*, of heavy cloth, as indicated in Fig. 13. This covering is provided with backwardly-turned flaps *e' e'*, which project an inch or two, more or less, from each side of the frame and engage the face of the 65 pneumatic sack and serve to prevent the rubber from bending sharply on itself as it bends over the frame and enters the sharp angles formed at each side thereof, as indicated in Figs. 3 and 4. I thus prevent a rupture or 70 perforation of the sack. This covering *e* is preferably of kersey or very coarse cushion-like fabric and is secured to said frame by means of stitches *f*, as shown in Fig. 13. The said kersey after being partly turned around 75 the frame is bent from the line of the screw-perforations *g*, so as not to interfere with the screws for attaching the hames to said frame, and the stitches cross back and forth from the opposite bends over said frame, as will be understood.

At the upper end of the frame, upon the sections *b b*, are secured the hinge-leaves *h h*, the latter being provided with sockets *i* to receive the same. Said hinge-leaves *h* are of 85 peculiar construction and comprise concavo-convex plates the front edges of which are turned upward to provide a rounded edge, conduced to the comfort of the animal. Into the hollowed top of the hinge-leaves and fitting around the said bosses for the frame-sections and raised lugs for the hinge-pin *c* are arranged wooden blocks *j*, which are rounded on their upper sides and give a smooth 90 100

curve to the collar above the hinge. The said bosses project up flush with the top of the blocks, and thus will not wear into the leather or other covering finishing the top of 5 the collar. Much greater lightness is thus secured than if the hinge-leaves and blocks were of one solid piece of metal, as well as a cheaper construction, and still a smoothness of the collar is not sacrificed by making the 10 hinge-leaves of irregular shape.

To prevent the pneumatic sack *k* from being injured by the metallic hinge parts of the collar, I have covered the under side of the hinge by a leather flap *l*. This is held in position by 15 a sheet-metal yoke *m*, having at its opposite ends ears *n n*, which are perforated to receive the hinge-pin *c*, the hinge-pin at its opposite ends passing through the said ears, as shown in Figs. 9 and 10. On the underside of the said 20 yoke, or the bar *m'* thereof, the flap *l* is fastened by means of rivets, as shown in Fig. 10. Said flap *l* lies on the under side of the cross-bar of the yoke, and is thus held away from the joints in the hinge, so as not to interfere with the hinge movement or be injured by the metal parts of the hinge. The 25 opposite extensions of the flap project from said yoke six inches, more or less, from the center of hinge movement, covering the metallic 30 parts of the hinge, so that the rubber of the pneumatic sack is protected from the possible sharp edges, all of which conduces to a greater durability and more perfect impermeability of the sack at the reduced top thereof. 35 Within the leather casing of the collar and on the inner sides of the flaps *e' l*, thus described, I have arranged the pneumatic sack *k*. This is shown in detail in Fig. 7 and consists of a single bag of impervious material, 40 such as vulcanized rubber. This is made diametrically smaller at the top of the collar, as at *k'*, and at the sides thereof is enlarged, as at *k²*, so as to bring increased cushioning effect at the shoulders of the animal to cushion the draft more perfectly. By forming 45 the opposite side cushions *k²* in one sack, extending over the top of the neck and down at the opposite sides thereof, I am enabled to inflate the two opposite cushions by the use 50 of a single inflated valve, and, furthermore, I reduce the number of joints that would otherwise be required, and thus secure less liability to permeability. Within the sack *k*, in the enlargement *k²* thereof, I have inserted 55 rolls or filling-pads *k³*, preferably of wool in the form of coarse textile fabric or loose unwoven wool, or other form of wool fiber may be employed, such as is able to withstand the heat required in the operation of vulcanizing the 60 outer impermeable inclosure or sack. These rolls or pads preferably do not extend into the normally bent or curved middle portion of the sack, but terminate considerably short thereof, as indicated by dotted lines in Fig. 65 7. I prefer, especially when the filling is of loose wool, to inclose the same in porous bags of proper form to hold the filling in place and

yet permit a free distribution of compressed air therethrough. The filling is first stuffed into the bags, proper shape and disposition 70 of material being secured, and then the bags are placed in the pneumatic sack, one at each enlarged end, as shown in Figs. 7 and 8 of the drawings. Thus the strain of stuffing is not exerted on the pneumatic sack, and, moreover, when said sack is repaired or replaced by a new one the filling can be removed in 75 the porous bags without being scattered or losing shape. The bags are inserted, it will be understood, before the pneumatic sacks 80 are sealed up.

The leather covering *o* is clamped at its longitudinal edges between the frame *b b* and the lames *a a*, the edges of the leather overlapping and being held in place between said 85 parts by the series of clamping-screws *p*, as shown in Figs. 1 and 2.

On the under side of the sack *k*, at the upper part of the collar, I have provided a second flap *r*, of leather, which covers the opening or space between the coverings of the two frame-sections *b*, where the ends of said sections are exposed for hinging together, it being understood that the coverings *o* for the two sections are two independent and separate coverings until connected, as now to be described. This flap *r* extends at its ends into the upper ends of the coverings *o o* and lies against the inner side, as shown in Fig. 9, and is provided with an upward-projecting tongue or tongues *q q*, which extend upward and over the hinge-pin *c*.

On the outer side of the leather coverings at the meeting top ends is a third flap *s*, which extends from side to side of the collar and at 100 its opposite ends is secured to the hinge-pin *c*. The said ends of the flap are held upon said hinge-pin by a suitable nut *t*, which holds the several parts together. The leather coverings at the top may be joined together by 110 a leather flap *u*, which may be sewed to said leather coverings at the overlapping edges, as shown at *v* in Fig. 9.

The last leather flap serves to cover the wooden blocks of the hinge and conceal the 115 parts from view.

The valve 3 for inflating the sack *k* is similar in construction to that of a bicycle-tire and may be of any arrangement of parts. By the outer flap *s*, secured to the opposite 120 ends of the hinge-pin *c* and extending beneath the upper part of the collar, a smooth bearing for the neck of the horse is provided, and all danger of the sack *k* being unduly inflated at this part of the collar, and appearing to view through the joints of the outer leather covering and thus becoming unduly exposed to direct contact with the animal, is 125 prevented.

At the lower end of the frame I have secured catches for holding the side sections of the collar together after the collar has been placed on the horse's neck, and to provide a 130 strong construction and one that will permit

of the collar being placed upon the horse with greater facility and ease I have provided the construction shown in Figs. 11 and 12, where the lower ends of the frame-sections 5 b b are shown to be provided with tubular heads 4 5, into which the forward sections are secured and firmly pinned. Said heads are of segmental shape and one part fits telescopically into the other.

10 The larger or female section 5 at one side is provided with a perforation 6, and the smaller section 4 is interiorly provided with a hooked catch 7, which is pivoted at its inner end and at its outer free end is provided 15 with an incline 8, adapted to cause the hook to enter the interior of the larger tubular head when the sections are brought together. A suitable spring 9 is inserted within the smaller end, which bears upon the hooked 20 catch and holds the same into its locking position. Thus when the parts are brought together, the smaller head entering the larger, so as to prevent any independent movement 25 of the parts laterally in any direction, the hooked end of the catch 7 is caused to enter the perforation 6 at one side of the larger head automatically, so that the parts are firmly locked together.

By means of the perforation 6 in the larger 30 head access is given to the hook after the same is locked, and thus by simply pressing on the hooked end of the catch with the finger the hook may be pressed back from catching relation with the larger head and the sections 35 may be easily separated to permit a removal of the collar from the horse's neck.

Having thus described the invention, what I claim as new is—

1. In a lock-collar, the combination with 40 frame-sections pivoted together at the top and having means for separable connection at the bottom, of a single pneumatic sack having enlarged ends arranged at the sides of the collar against said sections and a reduced 45 middle portion extending along the hinged upper ends of the sections and held thereto, said reduced middle portion permitting free action of the hinge and supporting the depending end portions, and said end portions 50 terminating short of the separable connecting means at the bottom of the collar, substantially as set forth.

2. In a lock-collar having frame-sections pivoted together at the top and separable at 55 the bottom, a single elongated pneumatic sack extending around the upright sides and the top of the collar and being supported at its middle portion to the frame-sections at their point of hinging, the end portions of said sack 60 depending at the sides of the collar and being adapted to cushion the said sections, said end portions terminating short of the point of separation of said sections at the bottom of the collar, substantially as set forth.

65 3. The improved horse-collar having a frame consisting of tubular sections, a covering inclosing said sections and secured thereto

along a longitudinal line at one side, flaps e, of soft cushion-like material sewed partly around the frame-sections and at the side 70 edges projecting laterally from said sections, and an elongated pneumatic sack within said covering and lying against the said cushion-like flap at the angles formed between the tubular frame-sections and covering, substantially 75 as set forth.

4. In a pneumatic collar, the combination with the frame, and covering fastened outside of said frame, of a cushion-like flap sewed partly around said frame, the opposite edges 80 projecting oppositely and adapted to lie in the angles formed by the frame and cover and a pneumatic sack protected at said angles by said flaps, substantially as set forth.

5. In a pneumatic collar, the combination 85 with the frame, a covering inclosing said frame and being fastened thereto along one side, cushion-like flaps secured to the frame and adapted to enter the angles formed between the covering and frame, and a pneumatic sack, protected at said angles, when inflated, by said flaps, substantially as set forth.

6. In a pneumatic collar, the combination 95 with the frame and covering, of a pneumatic sack within said covering and having air-tight walls, a bag within said sack whose walls permit free passage of air, and cushioning material in said bag, whereby said cushioning material may be removed from the sack in its bag 100 and its shape retained.

7. In a pneumatic collar, the combination of hinged frame-sections, a covering for each section, a rigid yoke lying beneath the hinge, a flap l, at its middle portion made fast to said 105 yoke and held away from the hinge and at its end portions lying against the adjacent ends of the sections, and a pneumatic sack protected from the hinge by said flap, substantially as set forth.

8. In a pneumatic collar, the combination of hinged frame-sections, a tubular covering for each section, a pneumatic sack having its end portions lying within said coverings and its middle portion extending from covering 115 to covering beneath the hinge of the sections, and a flap r, suspended from the hinge-pin and inclosing the middle portion of the sack, the ends of said flap being inserted between the sack and coverings, substantially as set 120 forth.

9. In a pneumatic collar, the combination of hinged frame-sections, a covering for each section, a pneumatic sack having its ends inclosed in said coverings and its middle portion extending across the hinge-joint on the inner side thereof, and flaps r, s, inclosing said middle portion of the sack and at their ends overlapping the coverings, one on the outside and one on the inside thereof, substantially as set forth.

10. In a horse-collar, the combination with tubular side sections threaded at their ends, of a hinge for joining the ends of said sec-

tions and comprising members cast from suitable metal and each consisting of a comparatively thin plate having at one end perforated lugs adapted to receive the hinge-pin and at 5 the other end bosses to which the frame-sections may be screwed, and a block of wood or other light substance filling the intermediate part of the hinge-leaf flush with the said bosses and lug, substantially as set forth.

- 10 11. In a horse-collar, the combination with the frame-sections, of a metal hinge, the leaves of which are turned upward at the forward side edges and provided at the ends with pivotal lugs for the hinge-pin and with bosses 15 in which the frame-sections are secured and blocks of wood or other light substance secured upon the central parts of the upper surfaces of the leaves and being flush at the top with the said pivotal lugs and bosses, substantially as set forth.
12. In a lock-collar, the combination with sections hinged at the top, of a catch for de-

tachably connecting their lower ends and comprising tubular male and female members secured one to each section and adapted to enter one into the other telescopically, the male member having interiorly a pivoted catch-hook and a spring normally holding said catch-hook in locking position, its end being suitably beveled to enter the female member automatically, and said female member having in its side wall an aperture serving the double purpose of providing a stop-shoulder for the catch-hook to engage in locking and a finger-opening for releasing the catch-hook in unlocking, substantially as set forth.

In testimony that I claim the foregoing I have hereunto set my hand this 19th day of October, 1898.

EDWIN L. BRUNDAGE.
